CANDY BAR

Thomas H. Powers, Westfield, N.Y., assignor to The Quaker Oats Company

Filed Mar. 22, 1972, Ser. No. 237,238

Term of patent 14 years

Int. Cl. D1—01

U.S. Cl. D1—21

FIG. 1

FIG. 2

FIG. 1 is a top view of a candy bar showing my new design;

FIG. 2 is a side view thereof with the other side being substantially of similar appearance; and

FIG. 3 is an end view thereof with the other end being of substantially similar appearance thereto.

I claim:

The ornamental design for a candy bar, as shown and described.
